United States Patent [19]

Claytor

[11] Patent Number: Des. 315,424

[45] Date of Patent: ** Mar. 12, 1991

[54] VERTICAL BARRIER FRESNEL LENS
ARRAY FOR INFRARED MOTION
DETECTOR SYSTEMS

[75] Inventor: Richard N. Claytor, Arlington, Tex.

[73] Assignee: Fresnel Technologies, Inc., Fort
Worth, Tex.

[**] Term: 14 Years

[21] Appl. No.: 316,435

[22] Filed: Feb. 27, 1989

[57] CLAIM

The ornamental design for a vertical barrier fresnel lens
array for infrared motion detector systems, as shown
and described.

DESCRIPTION

The single FIGURE is a front elevational view of a
vertical barrier fresnel lens array for infrared motion
detector systems showing my new design, the lens array
being a flat, rectangular, thin sheet having a front sur-
face with grooves thereon and a plain, smooth, rear
surface with no ornamentation.
